UNITED STATES PATENT OFFICE.

ANDREW B. BURT AND FRANK T. VANATTA, OF SAN FRANCISCO,
CALIFORNIA.

AUTOMATIC SIGNAL.

No. 806,319.

Specification of Letters Patent.

Patented Dec. 5, 1905.

Application filed June 5, 1905. Serial No. 263,782.

To all whom it may concern:

Be it known that we, ANDREW B. BURT and FRANK T. VANATTA, citizens of the United States, residing at San Francisco, county of San Francisco, and State of California, have invented certain new and useful Improvements in Automatic Signals, of which the following is a specification.

Our invention relates to automatic signals.

- 10 One object of the invention is the provision of novel means which will automatically indicate at any given point the exact part of the road the train is on at the time the signal is operated.
- 15 Another object of the invention is the provision of means for automatically indicating the direction in which the train is traveling.

Heretofore signals of this character exposed the signal to view, but did not indicate the direction in which the train was traveling, and when they did so indicate the signal was operated by separate mechanism. Our invention is designed to obviate this difficulty and to provide means which will not only indicate 25 the location of the train, but will at the same time indicate the direction of travel.

The invention consists in the novel arrangement and combination of parts, which will be fully described hereinafter and the novel features pointed out in the appended claims.

In the accompanying drawings, Figure 1 is a side elevation. Fig. 2 is a section at $\alpha\alpha$, Fig. 1, and showing in dotted lines the position of the tube when compressed by the car- 35 wheel. Fig. 3 is a section at $\gamma\gamma$ of Fig. 1, and Fig. 4 a detail section of a modified form of compressible tube.

Referring more especially to the drawings, 1 represents the ordinary rail, which is sup- 40 ported on cross-ties 2 of sufficient height at the point where the signal mechanism is located to give plenty of room. Rigidly secured to the rail, preferably over one or more cross-ties 2, is a chair 3, which has its top flush 45 with the tread of the rail and is provided adjacent the tread with a depressed portion 4, the purpose of which will be hereinafter described. Suitably secured to the rail at either end of the chair 3 are cylinders 5 of any suit- 50 able type, which are provided with pistons 6 and piston-rods 7. Connected to each of these cylinders and communicating therewith is a heavy compressible tube 8, which lies inter-

mediate the cylinders in the depressed portion 4 of the chair 3 and projects half of its 55 diameter or substantially double the thickness of the wall of the tube above the level of the tread of the rail, so that when the tube is compressed to its full extent it will have the aperture through it closed.

Depending from the piston-rods 7 are arms 9, which are provided with contact members 10, adapted to engage the contact-points 11 of two normally open circuits and to close the said circuits, according to the direction of 65 travel of the train.

The operation of the device is as follows: We will suppose, for instance, that the train is traveling in the direction indicated by the arrow a in Fig. 1. The wheel B will engage 70 and compress the tube, starting from the point marked C, and will, as it travels forward, force the air held in the tube into the cylinder at the right. This moves the piston in that cylinder forward, compressing the air ahead 75 and forming a partial vacuum in the cylinder on the left, so that when the wheel releases the tube, (but not until after the contact member has closed the circuit at the end,) the suction in the cylinder on the left caused by the 80 vacuum and the pressure ahead of the piston on the right tends to restore the parts to their normal position. It will be obvious that should the train be traveling in the opposite direction the device would operate in the 85 same manner, but would operate an entirely different signal.

To those versed in the art the uses to which this device will be and can be put are innumerable, and it will be evident that the 90 piston of the cylinders could be made to operate any class of signal other than an electric one. The tube might be sunk in a depression made in the rail itself, or otherwise, and we do not care to limit ourselves to the 95 exact construction shown, which is used for illustration only, but desire to cover broadly the many modifications which could be resorted to without departing from the spirit of the invention.

As shown at 8' in Fig. 4, the compressible tube may be made square or rectangular in cross-section with its opening normally of elliptical form, and we may prefer to use this form of tube in many instances.

Having thus described our invention, what

we claim as new, and desire to secure by Letters Patent, is—

1. A signaling device, comprising pneumatic means engageable directly by a moving body to operate independent signals to indicate the direction of travel of said body, and means for supporting said pneumatic means in engageable position.
2. In combination with a roadway, a tube held in juxtaposition thereto and engageable by a moving body approaching from either direction, independent pressure-operable devices connected to the respective ends of said tube, and independent signaling devices operable by the respective pressure devices aforesaid.
3. In a device of the class described, the combination with a rail, of a chair adjacent thereto, a pneumatic tube held on said chair adjacent the rail and adapted to be engaged by a moving body from either direction, and circuit-closing devices operated when the air is compressed in said tube by said moving body.
4. In a device of the class described, the combination with a rail, of a chair adjacent thereto, a pneumatic tube held on said chair adjacent the rail, and adapted to be engaged

by a moving body from either direction, cylinders connected to said tube, pistons in said cylinders, and circuit-closing devices operated by said pistons when the air from said tube operates said pistons.

5. In a device of the class described, the combination with a rail, of a chair adjacent thereto, a pneumatic tube seated on the chair and projecting above the tread of the rail, said tube adapted to be compressed from either direction by a moving body, cylinders connected to the respective ends of the tube, pistons in said cylinders adapted to be operated when the air is compressed in said tube by engagement with the moving body, a plurality of electrical-circuit contacts, and a contact member carried by each of said pistons adapted to close one of the circuits when the pistons are operated according to the direction of travel of the moving body.

In testimony whereof we hereunto affix our signatures in presence of two witnesses.

ANDREW B. BURT.
F. T. VANATTA.
